United States Patent Office

Des. 185,382
Patented June 2, 1959

185,382

MEDAL

Toru Nakagawa, Berkeley, Calif.

Application August 13, 1958, Serial No. 52,193

Term of patent 14 years

(Cl. D29—19)

The back of the medal is plain and unornamented.

I claim:

The ornamental design for a medal, as shown and described.
